FOLDING PORTABLE STEREOSCOPE

Jasper E. King and Vernon R. Powell, Denver,
Colo., dedicated to the free use of the People
in the territory of the United States

Application June 15, 1939, Serial No. 279,334

1 Claim. (Cl. 88—29)

(Granted under the act of March 3, 1883, as
amended April 30, 1928; 370 O. G. 757)

This application is made under the act of March 3, 1883, as amended by the act of April 30, 1928, and the invention herein described and claimed, if patented, may be manufactured and used by or for the Government of the United States of America for governmental purposes without the payment to us of any royalty thereon.

We hereby dedicate the invention herein described to the free use of the People in the territory of the United States to take effect on the granting of a patent to us.

This invention relates to stereoscopes and is more particularly concerned with the provision of a stereoscope which, when not in use, can be folded into a compact space.

In the accompanying drawing,

Figure 1 is a front elevational view of an embodiment of this invention as it appears when set up for use; Figure 2 is a plan view of Figure 1; Figure 3 is a front elevational view after folding the device; and Figure 4 is a rear elevational view of a fragmentary portion of the device showing the manner in which the sliding brackets are connected to the horizontal beam.

Referring with more particularity to the drawing, in which like numerals designate like parts, the device comprises a horizontal beam 5, the ends of which are inclined upwardly and inwardly at substantially 45°. Near the ends of said beam horizontal slots 6, 6 are provided. A pair of brackets 7, 7 are slidably engaged with said slots 6, 6, respectively, by means of screws 8, 8 and wing nuts 9, 9, said wing nuts permitting the brackets 7, 7 to be secured in position with respect to the slots 6, 6. Each of said brackets 7, 7 is provided with flanges 10, 10, respectively, to which are secured a pair of mirrors 11, 11, respectively, said mirrors facing each other and so disposed as to horizontally reflect images from the table plane, upon which the instrument is adapted to rest. A pair of legs or stanchions 12, 12, one for each of the flanges 10, 10, is secured to

said flanges, substantially as illustrated, the lower end of each leg being bracketed to a foot 13. The feet 13, 13 are of a hollow construction and are telescopably engaged with a pair of rods 14, 14, respectively, by means of which the base 5 support for the instrument may be increased.

Between the ends of the beam 5 a horizontal bracket 15 is secured extending between the mirrors 11, 11. On the end of said bracket 15 an eye piece is fixed, said eye piece consisting of a pair 10 of mirrors 16, 16, each one being parallel to one of said mirrors 11, 11, substantially as shown. The mirrors 16, 16 are spaced an optimum distance apart to accommodate the eyes of the user. The bracket 15 is provided with a concave surface 15 17 between the mirrors 16, 16 to enable the user to center his eyes over the mirrors without pressing his nose against the bracket 15.

Having thus described our invention, we claim:

A foldable stereoscope comprising a horizontal beam, said beam having its ends inclined inwardly and upwardly and having a horizontal slot at each end thereof; a pair of brackets, one for each end, pivotally and slidably engaged with its corresponding slot in said beam, said brackets being flanged so as to abut the inclined ends of said beam when said brackets are in their extreme outward positions; a pair of mirrors, each secured to one of said brackets and facing each other; stanchions secured to said mirrors; a telescopic base support secured to the bottom of each of said stanchions; a horizontal bracket secured to said beam and centered between the ends thereof; and a pair of spaced eye piece mirrors secured to said horizontal bracket, each one of said eye piece mirrors being substantially parallel to one of said first mentioned mirrors, the space between said mirrors being concave.

JASPER E. KING. 40
